UNITED STATES PATENT OFFICE.

HENRY D. MIXA, OF TWO RIVERS, WISCONSIN, ASSIGNOR TO TWO RIVERS PLATING &
MFG. CO., OF TWO RIVERS, WISCONSIN.

CHEESE-HOOP AND FOLLOWER.

1,249,801.

Specification of Letters Patent. Patented Dec. 11, 1917.

Application filed January 5, 1917. Serial No. 140,694.

To all whom it may concern:

Be it known that I, HENRY D. MIXA, a citizen of the United States, and resident of Two Rivers, in the county of Manitowoc and 5 State of Wisconsin, have invented certain new and useful Improvements in Cheese-Hoops and Followers; and I do hereby declare that the following is a full, clear, and exact description thereof.

10 The present invention relates to new and useful improvements in cheese hoops and followers.

In view of the relatively great length of various types of cheese hoops, it has been 15 found impracticable to form said hoops by drawing them from a flat sheet of metal and such hoops are usually constructed by riveting together the edges of a curved plate forming the wall of the hoop, and by securing 20 a separate bottom thereto. This method of construction is open to serious objection inasmuch as the securing means of the various parts considerably weakens the general 25 structure of the hoop, and further inasmuch as the seams of the hoop thus formed materially interfere with retaining the hoop in a desired sanitary condition.

It is therefore primarily the object of my 30 invention to improve the method of forming cheese hoops and other relatively elongated bucket shaped articles by drawing the wall portions thereof, whereby to procure a structure which is of maximum strength and which is seamless at its inner portion and 35 consequently sanitary.

Essentially, this major feature of my invention consists in drawing the bottom major wall portion from a single sheet of metal, and in drawing the outer wall portion 40 from a second sheet of metal and cutting off the bottom formed in the drawing operation. It is another further important object of my invention to utilize this cut off bottom of the outer wall portion as a 45 cheese hoop.

It is a still further object to so form this follower subsequently to its detachment from the outer wall portion, to procure a maximum strength thereof, and a most free 50 passage of whey therethrough.

With the above and other objects and advantages in view, the invention resides more particularly in the novel combination, formation and arrangement of parts herein-

after described and pointed out in the ap- 55 pended claims:

In the drawings:

Figure 1 is a side elevational view of a cheese hoop and follower constructed in accordance with my invention, the follower 60 and a portion of the hoop being broken away.

Fig. 2 is a side elevational view partly in section of the drawn body which forms the follower and outer wall portion of the hoop. 65

Fig. 3 is an elevational view of the finished follower.

Referring now more particularly to the accompanying drawings, the bottom 5 and the inner wall portion 6 of the hoop are 70 drawn from a single blank of metal, the bottom being provided with the usual whey passages 7. The outer wall portion 8 of the hoop comprises a seamless band telescopically receiving the adjacent edge of the inner wall portion, and this outer wall portion is formed by drawing a flat sheet of metal in cup form, as shown in Fig. 2 and in then cutting off the bottom and immediately adjacent wall portion of this cup on the line 75 A—A of Fig. 2.

The hoop thus formed is seamless with the exception of the seam formed by the juncture of its wall portions, and inasmuch as these wall portions are separable, this 85 seam does not interfere with cleaning the hoop to retain a desired sanitary condition thereof. Also, this seam does not affect the strength of the major portion of the hoop. The inner wall portion 6 is provided 90 with suitable handles 9, and disposed about said wall portion is a spacing ring 10 to hold the axis of the hoop in a horizontal position when the hoop is disposed in a press. 95

The cut off bottom of the cup shown in Fig. 2 which provides the outer wall portion 8 forms the follower 11 of the hoop, the periphery thereof being slightly reduced to fit within the outer wall portion 8, and in 100 this reducing operation the wall 12 is turned inwardly to seat the bottom of an adjacent hoop. The follower plate is provided with a series of openings 13 permitting passage of whey therethrough, and thus between 105 the follower plate and the inturned wall portion 12 is formed a circular whey chamber from which whey discharges through

openings 14 in the outermost portion of the wall. For bracing the follower plate, an annular band 15 is secured on that face of the plate adjacent the wall portion 12, this band comprising a strip of metal angular in cross section and provided with openings 16 in its outstanding wall, permitting free passage of whey therethrough.

While I have shown and described one preferred embodiment of my invention, it is obvious that to meet differing conditions of use, various modifications and changes of structure may be resorted to without departing in any manner from the spirit of my invention. It is also obvious that my method of forming the hoop may be also employed in forming other elongated bucket shaped members, and that therefore this feature of my invention is not limited specifically to cheese hoops.

What is claimed is:

1. A cheese hoop follower comprising a perforated sheet of metal having its edge portions bent laterally and inwardly, said edge portions being spaced from the face of the follower to provide a whey passage.
2. A cheese hoop follower comprising a

perforated sheet of metal having its edge portions bent laterally and inwardly and an annular bracing band on that side of the plate adjacent its inturned edge portions, said band extending from the body sheet of metal a distance equal to the distance between said body sheet and the rear face of said inturned edge portions.

3. A cheese hoop follower comprising a perforated sheet of metal having its edge portions bent laterally and inwardly and an angular bracing strip secured to that side of the plate adjacent its inturned edge portions, said strip being apertured in its out-turned portion to provide whey passages, said out-turned portion of the strip being of a width equal to the distance between the body sheet of metal and the inturned edge portions thereof.

In testimony that I claim the foregoing I have hereunto set my hand at Two Rivers, in the county of Manitowoc and State of Wisconsin, in the presence of two witnesses.

HENRY D. MIXA.
